(57) **CLAIM**

The ornamental design for a automobile tire, as shown and described.

DESCRIPTION

1. Tire tread

1.1 is a front elevation view of an automobile tire showing my new design;

1.2 is a rear elevation view thereof;

1.3 is a top plan view thereof;

1.4 is a bottom plan view thereof;

1.5 is a right side elevation view thereof;

1.6 is a left side elevation view thereof;

1.7 is a perspective view thereof; and

1.8 is an enlarged and partial front view thereof of the portion 1.8 in reproduction view 1.1.

The ghosted or low contrasted showing of portions of the automobile tire do not form part of the claimed design.
